FOLDING MACHINE

Carl A. Newhall, Peabody, Mass., assignor to
United Shoe Machinery Corporation, Borough
of Flemington, N. J., a corporation of New
Jersey

Application June 5, 1939, Serial No. 277,416

13 Claims.

(Cl. 12—54)

This invention relates to folding machines and is herein illustrated as embodied in a machine for folding the margins of pieces of sheet material used in the manufacture of boots and shoes.

Such machines are ordinarily mounted upon a long work-bench of standard height before which the operators are seated. It is desirable that the operator be free to assume a comfortable position while operating the machine and that all of the work-engaging members of the machine be exposed to view, so that the operator may readily see the operation of each of these members in the progressive folding of the margin of the work. To this end, the work-table of the machine of the present invention is located at substantially the level of the top of the work-bench, and the work is fed across the vision of the operator and not away from the operator, as has hitherto been the case.

Parts of the uppers of shoes, particularly of the fancy women's shoes now so prevalent, are frequently of very irregular shape, having in many localities sharply curved edges. In order to permit the folding of the margins along such edges, the space above the work-table is entirely unobstructed except for the work-engaging members, which project above it, and these members are arranged close together in a small space.

These and other features of the invention, including certain details of construction and combinations of parts, will be described as embodied in an illustrated machine and pointed out in the appended claims.

Referring now to the accompanying drawings,

Fig. 1 is a section on the line I—I of Fig. 6 of a machine in which the present invention is embodied, the direction of feed of the work being toward the observer;

Fig. 2 is a plan of the machine, all of the work-engaging parts which project above the surface of the work-table, with the exception of the combined gage and preliminary bender or plow, having been omitted;

Fig. 3 is a section of the work-table and the gage on the line III—III of Fig. 2;

Fig. 4 is a section of the work-table and the gage on the line IV—IV of Fig. 2;

Fig. 5 is a section on the line V—V of Fig. 10, the direction of feed of the work being from right to left;

Fig. 6 is a view of the greater part of the machine looking down upon it as it appears in Fig. 5, the work-table having been removed;

Fig. 7 is a detail in perspective showing more

particularly how the margin of the work is bent up to a predetermined extent by the gage and pressed down by the hammer;

Fig. 8 is a detail in perspective showing the relative positions of the lower feed-member and the anvil;

Fig. 9 is a detail in perspective showing the knife in process of slitting the margin of the work along a concavely curved edge;

Fig. 10 is a view, partly in plan and partly in section, of the machine as it appears in Fig. 11, all the work-engaging members except the knife having been omitted;

Fig. 11 is a view of the machine, partly in vertical section and partly in elevation, the direction of feed of the work being away from the observer;

Fig. 12 is a detail, partly in vertical section and partly in elevation, showing more particularly the mechanism for varying the rate of feed of the work;

Fig. 13 is a view, principally in elevation of the same mechanism viewed from the right of Fig. 12;

Fig. 14 is a detail in perspective of part of the mechanism for raising the feed finger to permit presentation of a piece of work to the machine;

Fig. 15 is a plan of certain of the work-engaging parts;

Fig. 16 is a detail, partly in vertical section and partly in elevation, showing more particularly part of the mechanism for varying the rate of feed of the work, the hammer and the anvil having been omitted; and

Fig. 17 is a view, principally in elevation, taken from the right of Fig. 16, the hammer and the anvil being shown.

Referring first to Figs. 1 and 2, the machine

comprises a hollow frame 21 in the form of a receptacle adapted to contain oil, the upper part of said frame being received in an opening in the work-bench 25 and being suspended from an annular plate 27, which is fastened to the work-bench by screws 29 and projects over the opening. The inner edge of this annular plate is rabbeted to receive the outer rabbeted edge of a work-table in the form of a plate 31, which is fastened to the annular plate by screws 32.

The work-table has an irregularly shaped opening in its center, through which project the feed finger 33, the knife 35 and the fold-presser or hammer 37. The other work-engaging member which projects above the level of the work-table is the combined gage and plow 39, this member

rising from one end of a flat stem which is adjustably fastened in a recess in the work-table by a screw 41, said screw passing through a slot in the stem and being threaded into the work-table. The work 100 is fed toward the observer, as viewed in Fig. 1. As viewed in Fig. 5, the work is fed from right to left, the operator occupying the position of the observer in that figure.

The provision of a machine having a work-table which is at the level of the top of the work-bench enables the operator to assume a less tiring position than has hitherto been the case; and the feeding of the work in a direction across the vision of the operator over a work-table so located, and with all of the work-engaging parts clearly exposed to view, facilitates the guiding of the work by the operator and enables him to detect instantly any fault in the folding of the work.

Referring to Fig. 5, the work is fed intermittently from right to left by the feed-finger 33 and a cooperating lower feed-member 43 (see also Fig. 8). The feed-finger descends upon the work to press it against the feed-member 43, then both these members are swung counterclockwise about the axis of a rod 45 to feed the work. The feed-finger then rises and the two members are swung back to repeat their cycle of movement. From the feed-member the work 100 passes to the gage 39 in the manner shown in Fig. 7. The work-engaging part of this gage comprises a portion which acts as a plow and bends up the margin of the work to form the fold and a portion which overhangs the edge of the work and, by determining the extent of the margin which is thus bent up, determines also the width of the completed fold. If the margin of the work is to be slit, for example if the fold is being made along the edge of a concave curve, as indicated in Fig. 9, this slitting is accomplished by the knife 35 which is caused to operate when desired, is located between the gage 39 and the hammer 37, and lies close to the adjacent substantially vertical face of the gage. The work then passes to the hammer which bends down and presses against the body portion of the work the margin which was turned up by the gage 39. An adhesive of some kind is employed which causes the folded-over margin to stick to the body portion of the work.

The lower feed-member 43 (Figs. 8 and 17) is formed at the outer end of a bent stem, the hub of which is loosely mounted on a short horizontal rod 47 which is supported by two spaced upstanding ears on a carrier 49, said carrier being mounted for oscillating movement on the rod 45. A compression spring 51, located between the stem of the lower feed-member and the carrier 49, tends at all times to hold the feed-member up against the underside of one end of an anvil 53, as shown in Fig. 8. The surface of the feed member 43, which contacts with the lower surface of the anvil 53, is very slightly convex. The lower feed-member, because of the spring 51, may yield when pressure is applied to it through the work by the feed-finger 33. The upwardly inclined stem of the feed-finger (Figs. 14 and 16) is adjustably clamped by a pinch-screw 55 in a pinch-bearing formed in a small casting 57, which is also mounted for swinging movement about the small rod 47. Beneath the tail of this small casting 57 (Fig. 17) is a compression spring 59, which urges the casting to rock about the rod 47 and thus to hold the lower end of a set-screw 61, which is threaded through the casting, in contact

with the upper end of a small plunger 63, said plunger being vertically slideable in a bore in the casting 49. At the lower end of the plunger is a head which fits in a slot in the casting 49 and carries a small roll 65 in position to be engaged and lifted once for every revolution of the shaft 67 by a small projection 69, on the rim of a rotary, otherwise flat-faced, cam 71 which is fast to the upper end of the shaft 67. The mechanism described above causes the feed finger to grip the work against the lower feed member and then to release it.

Between this gripping and releasing the carrier 49 is swung about the axis of the rod 45 to feed the work one step. Clamped upon the reduced cylindrical end of the carrier 49 (Figs. 12, 13, 16 and 17) by a pinch-screw 71 is the hub of an arm 73 having in it a segmental slot 75; and located in the slot is a small roll 77 rotatable on the smooth stem of a screw 79, said screw passing through a bore in the upper end of a link 81, through the roll 77 and being threaded into the upper end of an inclined link 83, the lower end of which is pivoted about the stem of a screw 85. This screw carries a small roll 87, which runs on a cam surface formed on a rotary cam-member 89, said cam-surface being smooth except for a raised portion 91 which acts through the link 83, once for each revolution of the cam-member, to rock the slotted arm 73 in one direction about the rod 45 and then to permit the arm to be rocked in the opposite direction. The roll 87 is held against its cam-surface, and the arm 73 is consequently rocked in said opposite direction, by a compression spring 93 (Fig. 10) located in a socket in a casting 95, which (Fig. 1) is fastened by cap-screws 97 to the bottom of the receptacle 21. The spring acts against a small block 98 (Fig. 10), which is held by the screw 85 and has rigid with it a guide in the form of a small cylinder 99 slideable in a socket in the casting 95.

The cam-member 89 is fast to the end of an inclined shaft 101 rotatably mounted in a bearing in the casting 95, said casting also having a vertical bearing in which is rotatably mounted the upright drive shaft 67 (Fig. 1) having, near its upper end, a spiral gear 109 which meshes with a spiral gear 111 fast to the upper end of the inclined shaft 101. The drive-shaft 67 is rotated by means of a pulley 113 from a treadle-controlled friction transmitter of the usual type, whereby the operator, by manipulating a treadle, can at any time start and stop the machine.

Returning now to Figs. 10, 12 and 13, the roll 77 on the screw 79 may be moved down in the slot 75, that is away from the rod 45, to decrease the lengths of the intermittent feed movements of the feed-finger and the lower feed-member, by pulling down upon a treadle rod 115 to swing down an arm 117, the hub of which is fast to one end of a rock shaft 119, to the other end of which is fast the hub of another arm 121, the free end of said arm 121 being pivoted to the lower end of the link 81. The arm 117 is normally held up by a spring 120 (Fig. 11) against a stop pin 123, so that the rate of feed of the work is normally at a maximum, but the operator may at any time depress a treadle, not shown, to pull down the treadle-rod 115 and thereby decrease the rate of feed. A stop-screw 122, which may be screwed into any selected one of a plurality of holes in a plate 124, serves to predetermine the extent of the intermittent feed movements when the treadle-rod 115 is pulled down.

The stem of the hooked knife 35 (Fig. 9) is fastened to a hub 125, which is pinned to one end of an inclined rock-shaft 127 mounted in the casting 95 (Figs. 10 and 11). Clamped to one end of the knife-shaft by means of a pinch-screw 129 is one end of an arm 131 carrying at its other end, by means of a screw 133, a roll 135 which, when permitted to do so, runs upon the periphery of the cam-member 89 and descends into a depression 136 in said periphery once for every revolution of the cam-member. The arm 131 is constantly urged downward by a tension spring 137 (Fig. 13), which is attached at its upper end to a small screw 139 threaded into the arm 131 and at its lower end to a small screw 141 threaded into a stationary part of the machine, these pins being shown also in Fig. 6. The arm 131 (Fig. 11) is normally held up so as to maintain the knife inoperative by an arm 143, the free end of which engages the underside of the outer end of the arm 131 and the hub of which is rotatable on a rock-shaft 149. The arm 143 is urged upward by a tension spring 145, which is stronger than the spring 137 and is fastened at its lower end to a screw 146 (Fig. 13) carried by the arm 143 and at its upper end to a stationary screw 147. In order to permit the arm 143 to be swung down when desired, so as to render the knife operative, one end of the hub of said arm (Fig. 10) has a shoulder in contact with a shoulder formed on a collar 151, which is fastened to the rock-shaft by a set-screw 153. At one end of the rock-shaft 149 is fastened the hub of a member having two arms 155 and 157. The outer end of the arm 155 is attached by a treadle-rod, not shown, to a treadle, also not shown, by which the arm may be rocked downward; and when it is so rocked the arm 143 is swung down to permit the roll 135 (Fig. 11) to ride into and out of the depression 136 in the cam-member 89 and thereby to actuate the knife, so as to slit the bent-up margin of the work, as shown in Fig. 9. The lower end of the treadle-rod 115, downward movement of which swings down the arm 117 to vary the rate of feed of the work, is attached to the toe-end of a treadle, not shown, to the heel-end of which is attached the lower end of the treadle-rod, not shown, the upper end of which is attached to the arm 155. Consequently, when the toe-end of this treadle is depressed, the feed of the work is retarded; and, when the heel-end of this treadle is depressed, the knife is rendered operative, the feed at this time being at a maximum determined by the position of the pin 123.

The arm 151 also has a treadle-rod, not shown, attached to it, the lower end of said rod being attached to the heel end of another treadle, not shown, depression of the toe-end of which operates the transmitter to start the machine. When the heel-end of this treadle is depressed to swing down the arm 157, the feed-finger 33 is swung up to permit presentation of a piece of work to the machine. To this end, the rock-shaft 149 has fast to it a hub 159 provided with an arm 161 which, when the arm 157 is swung down, is swung from right to left (Fig. 1). When the arm 161 is so swung, it swings another arm 163 clockwise about a small rod 165 upon which the hub of the arm 163 is mounted, said hub carrying a projection 167 (Fig. 14) which engages a bevelled lug 168 on the tail of the feed-finger-carrier 57. The downward thrust of the projection 167 against the bevelled face of the lug 168 causes two movements of the feed-finger.

It swings the feed-finger carrier 57 about the stud 47 to raise the feed-finger against the force of the spring 59 (Fig. 17) and it also causes the carrier-block 49, upon which the stud 47 is mounted, to swing to the right, as viewed in Fig. 16, about the rod 45 against the force of the spring 93. When the heel-end of the treadle rises by reason of the depression of the toe-end thereof after the leading end of a piece of work has been presented to the machine, the feed-finger is caused to descend upon the work by the spring 59 and is swung back to the left (Fig. 16) by the spring 93 to feed the work a little to the left just before power is applied to the machine.

15 The anvil 53 (Fig. 1) is formed at the upper end of an upwardly extending arm of an irregularly shaped lever 169, which is pivoted about the rod 165 and has a tail against which bears the lower end of a compression spring 171, the upper end of which bears against a screw 173. The spring 171 tends at all times to swing the lever 169 counterclockwise, as viewed in Fig. 1, the extent of this movement being limited by a stop-screw 175 which lies in the path of an arm 20 on said lever and is threaded into a collar 176 fastened to the rod 45. In Fig. 1, the anvil is shown in the position which it occupies when a piece of work is in the machine, the this is why the last-named arm of the lever 169 is not in contact with the stop-screw 175.

25 The work-engaging portion of the hammer 37 (Fig. 7) is a hardened block 177, having a V-shaped groove in its face to aid in plaiting the work along a convexly curved margin and is fastened by a screw to a bent stem, which terminates in a rock-shaft 179. This rock-shaft (Figs. 5 and 11), whose axis lies in a vertical plane which is parallel to the direction of feed movement of the work, is mounted in an inclined bearing in a part of the casting 95 and has fastened on its outer end by a pinch bolt 181 a short arm 183, to the extremity of which is pivoted by a screw 184 one end of a toggle-link 185, the other end of which is pivoted about the axis of a screw 187. The other toggle-link 189 is pivoted at its upper end about the axis of the screw 187 and at its lower end about the axis of a screw 191, which is threaded into the outer end of a bracket 193 bolted to the casting 95. 30 The toggle mechanism is broken and straightened to cause oscillation of the hammer-shaft 179 by a link 195, the upper end of which is pivoted about the axis of the screw 187 and the lower end of which is pivoted about the stem of a screw 197 threaded into the outer face of the cam member 89.

35 In a folding machine having a gage or similar member past which the work is fed, such gage exerts a pull or drag upon the unfolded margin of the work in a direction opposite to that in which the work is being fed; and this drag tends to the production of finished work which is more or less distorted or curled, this being particularly true, for example, when narrow straps are folded. In the present machine the pull or drag is counteracted by the action of the hammer which is mounted at the upper end of an inclined shaft, the arrangement being such that the hammer in its operative stroke has two components of movement, a downward component and a component in the direction of feed movement of the work, this latter component serving to counteract the drag or pull referred to.

40 As has been explained, the work-table of the machine is substantially flush with the top of

the work-bench from which the machine is suspended, and the operator is seated before the bench and occupies the position of the observer in Fig. 5, the work being fed from right to left. Due to this construction, the operator has at all times a clear view of the operation of the work-engaging parts and can at all times properly guide the work. Since these work-engaging parts occupy a small space and are the only portions of the machine which project above the surface of the work-table, the operator may readily fold the work when sharply curved edges are encountered. In the case of sharply curved concave edges, the difficulty is to be able to follow the curve—that is, to swing the work about a small radius without encountering any obstruction. In the case of sharply convex curved edges, the difficulty is to have the hammer so arranged that it will strike the work and press the fold. With the present construction in which only the work-engaging parts are above the level of the table and are located close together in the manner shown, both these difficulties are obviated.

Although the invention has been set forth as embodied in a particular machine, it should be understood that the invention is not limited in the scope of its application to the particular machine which has been shown and described.

Having described my invention, what I claim as new and desire to secure by Letters Patent of the United States is:

1. A folding machine having in combination, a frame in the form of a receptacle adapted to contain a supply of oil, means for supporting the receptacle beneath the top of a work-bench, a cover for the receptacle, said cover serving as a work-table the upper surface of said table being substantially flush with the upper surface of the work-bench and having an opening therein, work-engaging members including a feed-finger, a knife and a hammer extending up through the opening, and mechanism located entirely beneath the work-table and within the receptacle for operating said work-engaging parts.

2. A folding machine having in combination, a frame in the form of a receptacle adapted to contain a supply of oil, means for supporting the receptacle beneath the top of a work-bench, a cover for the receptacle, said cover serving as a work-table the upper surface of said table being substantially flush with the upper surface of the work-bench and having an opening therein, work-engaging members including a feed-finger, a knife and a hammer extending up through the opening, and mechanism located entirely beneath the work-table and within the receptacle for operating said work-engaging parts, said mechanism including an inclined rock-shaft at the upper end of which the hammer is carried.

3. A folding machine having in combination, a frame in the form of a receptacle adapted to contain a supply of oil, means for supporting the receptacle beneath the top of a work-bench, a cover for the receptacle, said cover serving as a work-table the upper surface of said table being substantially flush with the upper surface of the work-bench and having an opening therein, work-engaging members including a feed-finger, a knife and a hammer extending up through the opening, and mechanism located entirely beneath the work-table and within the receptacle for operating said work-engaging parts, said mechanism including an inclined rock-shaft at the upper end of which the knife is carried.

4. A folding machine having in combination, a frame in the form of a receptacle adapted to contain a supply of oil, means for suspending the receptacle from the top of a work-bench, a cover for the receptacle, said cover serving as a work-table, being substantially flush with the upper surface of the work-bench and having an opening therein, work-engaging members including a feed-finger, a knife and a hammer extending up through the opening, a casting rigidly fastened to and located within the receptacle, and mechanism mounted in the casting for operating the work-engaging members.

5. A folding machine having in combination, a frame in the form of a receptacle adapted to contain a supply of oil, means for suspending the receptacle from the top of a work-bench, a cover for the receptacle, said cover serving as a work-table, being substantially flush with the upper surface of the work-bench and having an opening therein, work-engaging members including a feed-finger, a knife and a hammer extending up through the opening, a casting rigidly fastened to and located within the receptacle, and mechanism mounted in the casting for operating the work-engaging members, said mechanism including a vertical drive shaft, a counter-shaft, a knife-shaft and a hammer-shaft, the three latter shafts being inclined.

6. A folding machine having in combination, a frame in the form of a receptacle adapted to contain a supply of oil, means for supporting the receptacle beneath the top of a work-bench, a cover for the receptacle, said cover serving as a work-table the upper surface of which is substantially flush with the upper surface of the work-bench, a plurality of work-engaging members projecting up through an opening in the table, a casting fastened inside the receptacle, and mechanism located entirely within the receptacle and supported by the casting for operating said work-engaging parts the entire space above the surface of the table, except for the work-engaging members, being free and unobstructed to permit the work to be turned freely.

7. A folding machine having in combination, a work-table having an opening therein, means for feeding the work over the table and for bending up the margin thereof to form the fold, and a hammer projecting up through the opening for pressing the fold, an inclined rock-shaft upon the upper end of which the hammer is mounted, and mechanism located beneath the table for rocking the shaft to cause the hammer on its pressing stroke to move both downwardly and in the direction of feed movement of the work.

8. A folding machine having in combination, a work-table having an opening therein, means for feeding the work over the table and for bending up the margin thereof to form the fold, and a hammer projecting up through the opening for pressing the fold, an inclined rock-shaft upon the upper end of which the hammer is mounted, and mechanism located beneath the table for rocking the shaft to cause the hammer on its pressing stroke to move both downwardly and in the direction of feed movement of the work, said mechanism comprising a toggle and means for straightening and breaking the toggle.

9. A folding machine having in combination, a work-table having an opening therein, work-feeding, fold-forming and fold-pressing instrumentalities, a knife projecting through the opening, an inclined rock-shaft upon the upper end of which the knife is mounted, and means located beneath the table for rocking the shaft.

10. A folding machine having in combination, a work-table having an opening therein, work-feeding, fold-forming and fold-pressing instrumentalities, a knife projecting through the opening, an inclined rock-shaft upon the upper end of which the knife is mounted, and means located beneath the table for rocking the shaft, said means comprising an arm fast to the lower end of the shaft and a cam for rocking the arm.

11. A folding machine having in combination, a work-table having an opening therein, a feed-finger, a knife and a hammer all of which project up through the opening, an inclined rock-shaft upon the upper end of which the knife is mounted, a second inclined rock-shaft upon which the hammer is mounted, a third inclined shaft, all three shafts being located beneath the table, means for rotating the third shaft, and means for causing said third shaft to rock the other two shafts and the feed-finger.

12. A folding machine having in combination, a work-table, work-feeding, fold-forming and fold-pressing instrumentalities, said instrumentalities including a co-operating feed-finger and lower feed-member, and a cooperating hammer and anvil, means for holding the hammer and

anvil from movement in the direction of feed movement of the work, and yielding means for holding a portion of the lower feed-member up against the under face of the anvil.

- 5 13. A folding machine having in combination a work-table provided with an opening, a stationary gage having an operative portion rising above the surface of the table over the opening, said gage being shaped to bend up the margin of 10 a piece of work fed past it, a lower feed member and an anvil both extending from below up into the opening, a feed finger cooperating with the lower feed member to feed the work past the stationary gage so as to bend up the margin of 15 the work, a hammer cooperating with the anvil, said gage being located between the hammer and the feed finger, a knife located between the gage and the hammer and arranged to cooperate with one face of the gage to make a shearing cut, and 20 mechanism located entirely beneath the table for operating the feed finger, its cooperating feed member, the knife and the hammer, the entire space above the surface of the table except for the work-engaging members being free and 25 unobstructed.

CARL A. NEWHALL.
